BY *S. Schofield* ATT'Y.

UNITED STATES PATENT OFFICE.

VINCENT W. WILSON, OF PAWTUCKET, RHODE ISLAND.

DESIGN FOR A GAME-BOARD.

SPECIFICATION forming part of Design No. 31,419, dated August 15, 1899.

Application filed May 10, 1899. Serial No. 716,293. Term of patent 3½ years.

To all whom it may concern:

Be it known that I, VINCENT W. WILSON, a citizen of the United States, residing at Pawtucket, in the State of Rhode Island, have invented and produced a new and original Design for a Game-Board, of which the following is a specification, reference being had to the accompanying drawing, forming a part thereof.

The figure represents a perspective view of a game-board, showing my new design.

The game-board A is provided at its surface with alternate stripes *a b*, of different colors, one series of which extends for the whole length of the board and another series for a portion of the length, as shown in the drawing. Space-lines *c c* are also provided upon the board transversely of the series of stripes

a b, thus dividing the stripes into several spaces *d d*.

The leading feature of my design consists in the two series of alternate stripes of different colors, the one series extending for the whole length of the board and the other series for a portion of the said length, the said stripes being divided into spaces by the transverse lines, as shown in the drawing.

Having now described my new design, what I claim as my invention, and desire to secure by Letters Patent, is—

The design for a game-board as herein shown and described.

VINCENT W. WILSON.
